UNITED STATES PATENT OFFICE.

THELMA E. CRUMLY, OF ST. LOUIS, MISSOURI.

DESIGN FOR A POWDER PUFF.

Application filed September 8, 1924. Serial No. 10,700. Term of patent 7 years.

To all whom it may concern:

Be it known that I, THELMA E. CRUMLY, a citizen of the United States, residing at the city of St. Louis and State of Missouri, have invented a new, original, and ornamental Design for Powder Puff, of which the following is a specification, reference being had to the accompanying drawing, forming part thereof.

In the drawing the figure is a front elevation showing my new design.

As shown in the drawing, the article consists of an ordinary circular disc powder

puff upon which is affixed the image of a baby's face. The more exaggerated features, such as the nostrils, eyes, mouth and eyebrows, are embroidered. The disc is embellished with ribbon, embroidery, lace and other trimming, so that the completed article is a fanciful hooded doll's head.

I claim:

The ornamental design for a powder puff, substantially as shown and described.

In testimony whereof I affix my signature this 28th day of August, 1924.

THELMA E. CRUMLY.
